UNITED STATES PATENT OFFICE.

JAMES C. BAILEY, OF GREENEVILLE, TENNESSEE.

RAIL APPLIANCE.

1,182,620.

Specification of Letters Patent.

Patented May 9, 1916.

Application filed September 10, 1915. Serial No. 50,046.

To all whom it may concern:

Be it known that I, JAMES C. BAILEY, a citizen of the United States, residing at Greeneville, in the county of Greene and State of Tennessee, have invented new and useful Improvements in Rail Appliances, of which the following is a specification.

The present invention relates to improvements in railroad construction, and among 10 the objects of the invention is to provide means for connecting the meeting ends of two railway rails; to sustain the rails against lateral or vertical movement but to permit of a limited longitudinal movement 15 incident to the expansion and contraction thereof; to provide means for vertically adjusting the rails at the ends thereof so that the heads of the said rails will be maintained in proper alignment; to prevent the 20 creeping of the rails; and to retain the rails of the track in proper spaced relation with each other to prevent the spreading thereof.

A further object of the invention is to provide a device of this character which 25 will embody the desirable features of cheapness as well as simplicity of construction, which may be readily and quickly applied to the rails and which will perform the functions for which it is adapted with accuracy and with surety.

With the above and other objects in view, the improvement resides in the construction, combination and arrangement of parts set forth in the following specification and 35 falling within the scope of the appended claims.

In the drawings: Figure 1 is a perspective view of a portion of a railway track provided with my improvement, and showing 40 the meeting ends thereof connected in accordance with my invention, Fig. 2 is a transverse sectional view approximately on the line 2--2' of Fig. 1, Fig. 3 is a horizontal section approximately on the line 3--3' of Fig. 2, Fig. 4 is a perspective view looking 45 toward the inner face of one of the joint chair members, Fig. 5 is a similar view of the wedge block, Fig. 6 is a similar view of the connecting rod, and the adjusting nuts 50 therefor, Fig. 7 is a similar view of the collar looking toward the inner face thereof, Fig. 8 is a similar view of one of the sections of the chair or fish plate employed 55 upon the rail opposite the joint, and Fig. 9 is a view in section illustrating the arrangement of a spacing bar upon one of the rails

and the connection of the same with the angle bar.

In the drawings the numeral 1 designates a railroad track, the rails 2, upon one side 60 of the track having meeting ends which are connected in accordance with the present invention.

The joint chair by which the meeting ends of the rails 2 are connected, comprises a pair of similar members 3--3, each of which includes a base 4 of a width approximately equaling or slightly less than one-half of the base flanges of the rail. The base, upon its outer edge, is formed with a depending side 5, the same being preferably of a length corresponding with the height of the ties 6, and the said side 5, adjacent the ends thereof is provided with openings 7 which receive the ties 6. The base, central of the 75 openings 7, is formed with outwardly extending horizontally disposed ears 8, the outer edges of the ears being notched to receive the retaining spikes 9, which, of course, enter the ties 6. Formed with the sides 5 80 and extending angularly over the base 4 are flanges 10 which terminate in vertical plates 11, and these plates are formed with openings which register with elongated bolt receiving openings in the webs of the rails 85 which receive securing bolts which are provided with the usual retaining nuts. The chair members 3 upon their outer longitudinal edges are centrally provided with vertically disposed depending members 12 and the base portions 4 of the said members are provided with right angular flanges 13 that are arranged in a line with the vertical edges of the said central member 12. The central portion 12 is provided with a substantially square opening 15, and the opening upon inner chair member is of a less area than the opening provided upon the outer chair member, but the upper walls or edges provided by each of the openings are 95 disposed a slight but suitable distance above the respective base portions of each of the chair members.

Secured between the side flanges 13 to the central portion 12 of the sides 5 of the chair member and resting upon the lower horizontal flange 14 thereof is a reinforcing strip or plate 16, the said plate being arranged flush with the lower wall provided by the opening 15, and if desired, the plate 16 may 100 be centrally recessed so that the same will be formed with side members which termi- 110

nate in a line with the side walls provided by the openings 15.

Passing through the openings 15 is a wedge block 17. This block, it will be noted, is arranged directly central with respect to the meeting ends of the rails, and by adjusting the same laterally of the rails the block will be elevated in the openings receiving the same and as a consequence elevate the meeting ends of the rails, so that danger of a "low" joint will thus be effectively prevented.

Arranged upon the rail 2 of the track opposite that provided with the chair member 3 are angle bars 18, the same being secured to the rail and to each other by suitable bolts passing through openings in the vertical plates and through similar openings in the webs of the rail, the said bolts being retained by the usual nuts. The horizontal flanges of the angle bars are provided with depending sides 19 which are of a depth approximately equaling the thickness or height of the ties 6. The side members 19, adjacent the ends thereof are provided with openings 20 to receive certain of the ties and formed with the upper edge provided by the said openings are laterally extending ears 21 which are notched to receive retaining spikes. The members between the openings 20, indicated for distinction by the numerals 22' are each provided with an alining opening 23, and passing through the said opening is a threaded rod 24. Nuts 25 are arranged upon the said rod, one of the said nuts contacting with the side of the outer angle bar and the other nut contacting with the central portion 22' of the side of the inner angle bar. By this arrangement it will be noted that the rod 24 may be laterally adjusted with relation to the angle bars, and, if desired any suitable means may be employed for retaining the nuts against unscrewing upon the rod. The opposite end of the rod 24 passes through a central opening in the wedge-block 17 and has its outer end provided with an adjusting nut which contacts with the outer and widened face of the said block 17. Arranged upon the rod 24 is a slidable sleeve or collar 26, the same having its inner face of a hollow substantially rectangular formation, as indicated by the numeral 27, and this portion is adapted to be arranged against the inner section of the chair member and to receive the reduced end of the block, when the said block is adjusted laterally to elevate the rail ends. Contacting with the outer face of the sleeve 27 is a nut 28, and it will be noted that by manipulating the said nut 28 and the nut secured to the outer end of the rod 24, the said rod may be adjusted to properly space the rails of the track. It will be further noted that the peculiar arrangement of the

side members of the angle bars permits of a great amount of the roadbed being received between the central members 22' thereof as well as the portions outward of the openings 20, and as stated the side members may depend below the ties and thus it will be seen that the said members so grip in the roadbed as to effectively prevent the lateral movement of the same. This is also true of the members provided upon the sides 75 5 of the chair members outwardly of their openings 7, and the simplicity and advantages of such a structure will, it is thought, be perfectly apparent.

If desired, in lieu of the rod 24 having its ends provided with threads receiving adjusting nuts, a rod 29 may be employed, the said rod having one of its ends flattened, as at 30, and provided with an inturned lip 31, its opposite end being threaded. Secured to 80 the flattened end of the rod is a clip 32, and one of the rails 2 is adapted to be received between the clip and the lip. The threaded end of the rod may pass through the openings 23 in the central member of the angle bars 18 or the said end may be passed through the opening in the wedge-block 17. In either event, nuts 33 and 34 are provided upon the threaded end of the rod to contact with both the inner and outer faces of the 85 side members of the angle bar or with the inner and outer faces of the adjusting block.

Having thus described the invention, what I claim is:

1. In combination, a track, a chair member for the meeting ends of the rails upon one side of the track, said chair including a base upon which the rails rest and having depending sides provided with openings to receive certain of the supporting ties for the rails, lateral ears above the openings having notches for securing spikes, said depending sides having a central wedge-shaped opening, a wedge block arranged within the opening and providing a rest for the meeting ends of the rails, means for laterally adjusting the wedge block, and said means having a connection with the opposite rail of the track.

2. A track, a chair connecting the meeting ends of the rails on one side of the track, said chair including a base upon which the rails rest, side members received in the fishing spaces and connected with the rails, said chair also including side extensions provided with openings adjacent their ends to receive ties of the track, the said side members having lateral ears resting upon the ties and secured thereto, a wedge block passing centrally through the chair and receiving the meeting ends of the rail, means for adjusting the wedge block to elevate the rail ends, said means having a connection with the rail of the track opposite the joint.

3. A track, a joint chair for securing the

meeting ends of rails on one side of the track, said chair comprising two companion members each including a base having flange members arranged in the fishing spaces of the rails and secured to said rails, each of said members having depending sides provided with spaced openings to receive certain of the ties of the track, and means for securing the members to the said track, the 10 central portion of the members at the depending sides thereof having inwardly extending flanges and being provided with openings of different areas between the flanges, reinforcing plates for the bottom and side walls of the said opening, a wedge block passing through the openings and receiving the meeting ends of the rails, a longitudinally adjustable rod passing through the block, nuts for the rod, a collar includ-

ing a hollow substantially rectangular member contacted by one of the nuts and adapted to receive the reduced end of the wedge block, fish plates for the other rail of the track, said plates having depending sides provided with openings through which the 20 ties pass, the mentioned rod passing through openings in the central portion of the depending side, nuts upon the rod contacting with the outer faces of said sides, and the sides, central of the openings, having lateral 30 ears, and securing members passing through the ears and entering the tie.

In testimony whereof I affix my signature in presence of two witnesses.

JAMES C. BAILEY.
